UNITED STATES PATENT OFFICE.

ABRAHAM CRESSY MORRISON, OF ESSEX FELLS, NEW JERSEY.

METHOD OF TREATING GASES.

1,273,929.

Specification of Letters Patent. Patented July 30, 1918.

Application filed April 4, 1914. Serial No. 829,630.

To all whom it may concern:

Be it known that I, ABRAHAM CRESSY MORRISON, a citizen of the United States, residing at Essex Fells, in the county of Essex and State of New Jersey, have invented certain new and useful Improvements in Methods of Treating Gases, of which the following is a specification.

My invention has for its object to so treat a gaseous mixture, such as air, composed of two or more gases of different specific gravities, as to obtain therefrom a gaseous mixture containing relatively greater proportions of one or more of the ingredients than are found in the original mixture.

More specifically, my invention relates to the treatment of atmospheric air for the purpose of producing therefrom a product containing more oxygen than is present in air; and relates further to the use of such oxygenated air in the liquefaction of air, and for other purposes.

Air contains about 21 per cent. by volume, and about 23 per cent. by weight of oxygen, in mechanical mixture with nitrogen, the atomic weight of oxygen being 16 and that of nitrogen 14. It is also known that gaseous oxygen is magnetic and that liquid oxygen is more strongly magnetic; and my invention further relates to a means for concentrating or oxygenating air by the combined effects of magnetic and physically produced forces.

My invention may be carried out in apparatus such as is shown in the accompanying drawings, in which—

Figure 1 is a schematic representation of the apparatus;

Fig. 2 is a sectional elevation of the centrifugal coil, on a larger scale than in Fig. 1;

Fig. 3 is a section through the end portion of the coil.

Referring to Fig. 1, A is an air-compressor in which the air may be compressed to any desired degree. B is a cooler for extracting the heat of compression from the compressed air, from which the air is delivered into a receiving-tank C. From the receiving-tank, the compressed air may pass either through pipe 1 to the engine D, where it is expanded while doing work; or it may pass directly from the tank C through the pipe 2 to the centrifugal coil E. The intensely cold exhaust from the engine D may also be delivered through the pipe 3 to the

coil E. Both pipes 2 and 3 are provided with suitable valves and deliver compressed air to the coil E through a suitably shaped nozzle 4 by which additional velocity is imparted to the current of air. The coil E consists of a tube preferably oval or elliptical in cross-section, the coils of the spiral being of gradually decreasing diameter. At or near the end of the coil, there is inserted a partition or partitions 5 and 6, thus dividing the end portion of the pipe into two or three chambers from which extend delivery pipes 7, 8, 8'. The coil E is inclosed within the pole-pieces F and G of a powerful electromagnet to which current is delivered by a dynamo H or other source of electrical energy. From the coil E, the pipe 7 may deliver directly to a liquid air apparatus I or may first pass through a second coil E' similarly provided with means for establishing a strong magnetic field between the pole-pieces F', G' of a second electromagnet also energized by the dynamo H. The pipe 7 is connected to the inner coil of a counter-current refrigerating-apparatus of the well-known Linde type, the inner pipe 9 of which is surrounded by an outer pipe 10. From the lower end of this coil, pipe 9 passes through the coil 11 immersed in the liquid oxygen receptacle 12 and thence to the expansion nozzle 13 from which the now liquefied gas passes through pipe 14 to the top of a rectifying-column 15, the liquefied oxygen passing downward over the shelves of the rectifier and collecting in the receptacle 12. The nitrogen vapor passes out of the pipe 16 into the tube 10 and absorbs heat from the gas passing through the inner pipe 9.

The receptacle 12 is surrounded by the pole-pieces 17, 18 of a powerful electromagnet, in order that there may be produced within the receptacle a powerful magnetic field. The expansion nozzle 13 is similarly surrounded by pole-pieces 19 and 20 of an electromagnet, these two last-mentioned electromagnets being furnished with current from any suitable source of electric energy, such as the dynamo H. 50, 51 are the pole-pieces of still another electromagnet, and it will be advantageous to use such magnets at other points in the apparatus wherever air is being separated from nitrogen or other non-magnetic gases, and particularly where the air is at, near, or below its liquefying point.

The operation of the device is as follows:—

Air is compressed in the compressor A to any desired extent. If the air is to be cooled by expansion in the engine D, the air should be compressed to a high degree, as for example 200 atmospheres. If the air is not to be preliminarily cooled by expansion, the compression need not be carried to so high a degree, from 50 to 100 pounds being sufficient. In either event, the compressed air is preferably taken through the cooler B to remove the heat of compression. The compressed air either directly from the tank, or exhausted from the engine cylinder, is then delivered into the coil E through a nozzle 4, by which it is given a high velocity. This velocity may be, by the use of a nozzle of the proper shape and with air at suitable temperature and under suitable pressure, as high as 3,000 or 4,000 feet per second, but should not be less than the molecular speed of movement. The centrifugal forces acting upon the air as it passes through the spiral 25 coil at this high velocity will tend to throw the heavier oxygen to the outer portion of the oval tube with the result that there will be produced near the outer periphery a layer or zone containing more oxygen than that 30 contained in the inner portion of the tube, which part of the tube will contain a mixture correspondingly richer in nitrogen. This centrifugal separation is accentuated by the location about the coils of the pole-pieces of a powerful electromagnet. The strong magnetic field thus produced will still further tend to cause the magnetic oxygen to move in the same direction as that in which it is moved by the centrifugal force. 40 The result of these combined forces acting on the oxygen will be to cause a concentration of the oxygen in the outer zone of the coil from which it can be removed for use in any desired manner.

45 The use of such a gaseous mixture containing a larger percentage of oxygen than is normally present in air is of great advantage in processes of manufacturing oxygen by the liquefaction of mixed oxygen and nitrogen. I have illustrated such a use. When so used, the magnetic properties of liquid oxygen may be still further utilized, both before and after the liquefaction, in order to facilitate the liquefaction itself and as a means for improving the rectification of the liquefied gases to obtain therefrom the oxygen and nitrogen in a commercially pure state. This feature of my invention is carried into effect by locating in proximity to the liquefaction nozzle 13, electromagnets by which there will be produced a powerful field of force through which the air to be liquefied will pass. As the air approaches the dew-point, i. e., that 60 65 degree of temperature at which globules of

liquid air tend to form or are formed, the magnetization of each of the oxygen molecules will cause a mutual attraction which will increase their tendency to aggregate into drops and tend to augment the size of 70 the drops when formed.

The strong magnetic field produced in the receptacle 12 will serve to there assist in retaining the liquid oxygen, so that the nitrogen will be more completely separated, in 75 accordance with the principle of operation of my prior Patent No. 1,056,043, granted March 18, 1913.

When a gas, such as air, at very high pressures, is allowed to expand while doing work, 80 the temperature of the air is reduced. Thus, if air at a pressure of 4,000 pounds to the square inch, be allowed to expand to a pressure of 60 pounds to the square inch, the drop in temperature will be about 185°, so 85 that the exhaust air will be at a very low temperature, while still under sufficient pressure to impart the requisite velocity for centrifugal separation. If, when the air at this low temperature is subjected to the combined centrifugal and magnetic forces, as in 90 the process and apparatus above described, there will result a concentration of oxygen which will obviously produce great economies in the subsequent process of liquefaction. 95

It will of course be understood that all the apparatus in which refrigerated gases are used are to be provided with proper heat-insulation, in order to minimize heat losses, 100 and no attempt has been made to illustrate such heat-insulation.

It will be further obvious that my invention is capable of use for many other purposes than the liquefaction of air, since oxygenated air will be of great value in all locations where combustion is effected, as in blast furnaces, gas-producers, and furnaces of other kinds; and it will be further evident that the centrifugal action alone, and without the use of the magnetic features above described, will produce air richer in oxygen available for the purposes mentioned. 110

As a matter of theory, it would seem to be clear that the action of a magnetic field of force upon the molecules of oxygen or other paramagnetic gas is the same as its action upon any other magnetic substance, that is, that each molecule when in such a magnetic field of force becomes an individual magnet. It would seem further that the only difference between the apparent paramagnetic characteristics of oxygen in a liquid form and as a gas is the difference due to the different density. Thus, if a paramagnetic gas like oxygen be assumed to be at a temperature so low that condensation is about to take place because of the diminution of molecular movement resulting from abstraction of heat-energy, the nat- 120

ural cohesion of the molecules may be assisted by the superinduced magnetic attraction for each other, with the result that liquefaction takes place more quickly or at a 5 slightly higher temperature than would otherwise be the case. Obviously, any means by which the liquefaction temperature of a gas can be in effect raised, will be of great practical advantage, not only in the liquefaction 10 of the particular gas, but in the rectification of liquefied mixed gases.

Referring to Figs. 2 and 3, it will be noted that two partitions 5, 6 are shown, although only one may be used in case the 15 gas is to be separated into only two portions.

What I claim is:—

1. The method of treating mixtures of oxygen and other gases, which consists in 20 subjecting the mixture simultaneously to centrifugal and magnetic forces.

2. The method of treating mixtures of oxygen and other gases, which consists in subjecting the mixture to centrifugal action 25 tending to separate the heavier from the lighter gases while the mixture is in a strong magnetic field.

3. The method of treating mixtures of paramagnetic and non-magnetic gases, which 30 consists in simultaneously subjecting the mixture to centrifugal and magnetic forces.

4. The method of treating mixtures of oxygen and other gases, which consists in cooling the mixture and then simultaneously 35 subjecting the mixture to centrifugal and magnetic forces.

5. The method of treating mixtures of oxygen and other gases, which consists in 40 cooling the mixture to approximately the liquefying point while in a powerful magnetic field.

6. The method of separating the apparent 45 boiling-points of mixed paramagnetic and diamagnetic liquids, which consists in subjecting them to the action of a magnetic field.

7. The method of treating air, which consists in causing the air to flow at high velocity through a spiral tube located in a strong 50 magnetic field, and separately removing

gases from the outer and inner portions of the tube.

8. The method of treating air, which consists in compressing the air, cooling it and causing it to flow at high velocity through 55 a spiral tube located in a strong magnetic field.

9. An apparatus for centrifugal treatment of gases, comprising a spirally-arranged tube, and means for producing a magnetic 60 field about said tube.

10. An apparatus for centrifugal treatment of gases, comprising a spirally-arranged tube having a longitudinally-arranged partition at the end of such tube, 65 means for removing the gases from the chambers formed by said partition, and means for producing a magnetic field about said tube.

11. An apparatus, comprising means for 70 liquefying gases, comprising an expansion nozzle, and means for producing a magnetic field about said nozzle.

12. An apparatus for treating air, comprising a compressor, means for cooling the 75 air including an expansion engine, a spiral tube connected to the engine exhaust, and means for producing a powerful magnetic field about said tube.

13. An apparatus for treating air, comprising a compressor, means for cooling the air including an expansion engine, a spiral tube connected to the engine exhaust, and means for producing a powerful magnetic field about said tube, said tube provided 80 with means for removing gases from the outer and inner portions.

14. The method of liquefying a paramagnetic gas at a temperature slightly above the normal boiling-point, which consists in 90 subjecting the gas to the action of a powerful magnetic field, thereby causing liquefaction to occur above the normal boiling point.

In testimony whereof I affix my signature in presence of two witnesses.

ABRAHAM CRESSY MORRISON.
